PULVERIZER MILL

Harry R. Collins, Allentown, Pa.; May H. Collins
administratrix of said Harry R. Collins, deceased

Application October 1, 1934, Serial No. 746,343

11 Claims. (Cl. 83—45)

This invention relates to pulverizer mills and more particularly to mills of the type in which the grinding devices comprise one or more annular series of grinding elements, preferably 5 balls, which cooperate with grinding surfaces, at least one of which rotates in a horizontal plane to actuate the balls. The mill is especially intended for the reduction of non-metallic materials, such as coal, limestones and cement clinker, 10 and is well-adapted for either wet or dry grinding.

It is among the purposes of the invention to produce a mill of simple mechanical design, and which can be manufactured at much lower cost 15 than those now available for similar uses. To this end, the design further contemplates the safe use of cast-iron as the principal material of construction, with a minimum number of steel or alloy parts. Among its more important 20 mechanical features is the arrangement of the grinding and driving mechanisms as separate assemblies, independently supported and self-centering. The complete driving mechanism can be assembled and installed or removed as a unit without disturbing the grinding elements, which 25 are thus made readily accessible. For purposes of efficiency in grinding and control of particle sizes, I prefer to accomplish the reduction of material in at least two stages, by the use of two 30 or more series of grinding balls and their co-operating grinding surfaces, and contrary to conventional practice to apply the maximum pressure 35 to the grinding elements of the first stage.

For this purpose, the rotating grinding surfaces or discs are vertically movable, and their 40 combined weight, together with the weight of the balls of the second or other stages is carried by the grinding balls of the first stage. This weight is less than that desirable to effect the first stage of reduction, and the required additional pressure is applied by adjustable spring 45 means, which not only permits the application of the most favorable pressures to the secondary stages, but likewise applies the additional pressure to the grinding elements of the first stage. Thus the crushing and grinding effect of the first stage is increased considerably as compared with older types of mills, and the final reduction is accomplished in the secondary stage or stages, 50 where relatively less pressure is required, with the result that particle sizes are more nearly uniform, and the power requirement relatively low. Further, the pressure applied by the spring means and the weight of the balls and rotating 55 rings is transmitted to the fixed ring, whereby

the entire grinding assembly may be removed as a unit to expedite repairs or replacement. Thus, instead of a plurality of supports for the grinding elements, as in conventional practice, the fixed ring is the sole support, and the mill 5 is accordingly a self-centered, ball-bearing machine. The symmetrical arrangement of both the driving and grinding assemblies about the vertical axis of the mill provides for simplicity in construction, maintained alignment, decreased 10 vibration and consequently relatively decreased wear of the working parts and quiet operation.

The driving and speed reduction devices are so designed that the balls are driven in their race-ways at a speed corresponding approximately to the rate of fall of material entering 15 the grinding surfaces, for if the balls move too rapidly, they will merely wear out without accomplishing any greater result; and conversely if the speed is too low, coarse particles falling 20 by gravity will slip between the balls and pass to the next stage or out of the mill before the desired reduction is made.

A vertical arrangement of the grinding and driving assemblies, with the latter at the top, 25 makes it possible to employ a simple and effective means for wet or dry classification, and forwarding of the pulverized materials. In dry grinding, the classification apparatus has the advantage that instead of blowing the air stream 30 through the mill, or air sweeping the mill itself, the air is drawn into the mill below the grinding elements, whereby the fines are discharged without carrying coarse particles with them. This 35 principal of classification is substantially preserved in the grinding of damp materials, as the volume of heated air or gas used for drying is controlled so that the air sweeping of the grinding elements does not occur. A similar arrangement of parts is employed for wet grinding, as 40 will appear more fully hereinafter.

In general, the preferred form of the new apparatus comprises a cylindrical casing, made up of sections which are self-centered, by means of V's and corresponding grooves in adjacent 45 surfaces, the arrangement providing for simplified machining and maintained alignment of the parts. The lowest section carries the fixed grinding ring, a central section carries the support for the main bearings of the driving equipment. 50 The driving mechanism preferably includes a vertical motor of the ball-bearing type, secured by its flange to the upper surface of the casing. The motor shaft may be provided with a pulley for driving a feeder of any suitable type, which 55

- will deliver a continuous flow of material to the grinding elements. The motor shaft also carries a hardened steel pinion, which drives two or made oppositely arranged idler gears.
- 5 The idler gears drive a ring gear, carried by a spider, the latter being supported and secured to the main driving shaft of the grinding elements. This shaft is flanged at its upper end, and countersunk to receive the upper race of a ball 10 thrust bearing, carried by a support between the central and upper sections of the casing. The upper section of the main shaft is cylindrical, and carries a radial bearing arranged in a central cavity in the said support. Suitable packing 15 is provided below the bearing, to preclude the entrance of dust along the main shaft and into the driving assembly.
- The lower section of the main shaft is of square or other angular section, and is surrounded 20 by two grinding rings or discs, movable vertically thereon, and provided with central openings slightly larger than the shaft, whereby a limited lateral movement is permitted to maintain the desired alignment of the grinding surfaces 25 regardless of inaccuracies in manufacture or the effect of wear, as will appear more fully hereinafter. This limited motion also permits a rotating grinding ring to rise to permit the balls to discharge tramp iron or other foreign material 30 without injury to the grinding elements. The under surface of the upper movable grinding ring is provided with a chilled circumferential grinding surface, curved to correspond substantially with the curvature of an annular series 35 of grinding balls. These balls are carried in a similar channel formed in the upper surface of a fixed grinding ring, secured between the lower and central sections of the casing.
- The second stage comprises a similarly curved 40 chilled surface, formed on the under surface of the fixed ring, and it, with a channel formed in the upper surface of a second movable grinding ring, forms a race-way for the balls of the second stage.
- 45 The two movable grinding rings are drawn together with spring rods, provided with compression springs, whereby the pressure on the grinding balls may be adjusted in accordance with the characteristics of the material to be ground.
- 50 For classifying and forwarding dry ground materials, the lower movable grinding ring is provided with a circular dam, adjustable vertically to control fineness of the material discharged. Air for sweeping and forwarding the material 55 enters the mill through a circular series of ports in the casing below the lower rotating ring, due to the action of a fan, the casing of which closes the lower end of the mill casing. To drive the fan, a pinion shaft, secured to the motor shaft, 60 is provided with a coupling hub extension, to which the fan shaft is secured. This shaft extends through a central bore in the main shaft, and is centered in a radial bearing in the bottom of the fan casing, the fan being secured to 65 the fan shaft immediately above the bearing. The fan is thus driven at the full load speed of the motor, which conveniently may be 690 R. P. M., while the balls are driven at a speed corresponding to the gravity fall of material, as 70 described above. By this arrangement, particle sizes can be closely controlled and the product will be much more nearly uniform in size, as compared with mills of other types, as the air stream 75 does not sweep the grinding elements, and carry coarse particles with it.

For wet grinding, the general arrangement of parts is the same. A slurry pump, similarly located and driven, is substituted for the fan; the ports in the casing are omitted; and a second adjustable dam is carried on the inner edge of the 5 fixed grinding ring to control the fineness of material discharged from the first stage.

The design also lends itself especially well to the efficient grinding of damp materials, such as raw coal, and only minor structural changes and 10 additions are required. The air inlet ports are surrounded by a volute casing or wind box, into which air or gas, preferably preheated, from any suitable source, is forced or drawn into the mill. The air is admitted in sufficient volume so that, 15 in addition to the quantity required by the mill fan for forwarding the material, a counter-current is drawn upwardly through the descending material to evaporate the free or surface moisture. The volume and velocity of the drying air 20 is held to the minimum necessary for efficient grinding. The drying air is drawn from the mill above the grinding elements, by the usual exhaust fan and discharged into an air separator of any suitable type for recovering any suspended dust. 25

It is especially to be realized that by maintaining this low-velocity counter-current, air sweeping of the grinding elements is avoided, and that the operation is not to be confused with conventional methods of air classification or closed-circ- 30 uit grinding.

For a better understanding of the invention, reference is made to the accompanying drawings, in which:

Fig. 1 is an elevation, partly in section, of the 35 preferred form of the invention;

Fig. 2 is a similar elevation, partly fragmentary, of a modified form of the mill, adapted for wet grinding, and

Fig. 3 is a similar elevation of the mill as adapt- 40 ed for grinding damp materials.

Referring to the drawings, and first to Fig. 1, the apparatus will be seen to consist of a cylindrical casing 1, comprising a lower section 2, a central section 3 and an upper section 4, the 45 lower section 2 being provided with an annular flange 5, which serves as a bed-plate for the apparatus.

A fixed grinding ring 6 is secured between the lower and central sections, and a main bearing 50 support 7 is secured between the central and upper sections, each of the parts above described being centered by V's 8 which correspond with grooves cut into the adjacent surfaces and the sections together with fixed ring 6 and support 7 55 are secured by the usual through bolts several of which extend only through the lower flange of the upper section 4 and the support 7. The casing is closed at the top by means of a cover-plate 9, provided with bosses 10, to which a flange 60 of a vertical motor indicated at 11 is secured in the usual manner.

The complete drive assembly is arranged within a compartment provided by the upper section 4, the bearing support 7 and the cover-plate 9. The 65 motor shaft is provided with a pulley 12, to receive a belt 13 for driving a feeder generally indicated at 14, the feeder discharging at 15 into the central section 3. The shaft of the motor is provided with a hardened steel pinion 16, which 70 drives oppositely arranged idler gears 17 and 18, carried by bearings on suitable vertical shafts, secured to the cover-plate 9. The idler gears mesh with a ring gear 20, carried by a spider 21, the latter being secured to a flange formed on 75

the upper end of the main driving shaft 22. The flange is recessed to receive the upper race-way of a ball thrust bearing 23, the lower race of which is carried by the bearing support 7.

5 The upper end of the main driving shaft 22 is cylindrical, and is surrounded by a radial roller bearing 24, arranged in a central bore of the support 7. Below this bearing a groove is provided at 25, to receive packing of any suitable type, to 10 preclude the entrance of dust along the shaft and into the driving mechanism. It will thus be seen that by removing the bolts which pass through the three flanges and lifting the upper section 4, the entire drive assembly can be removed as a 15 unit to permit ready access to the grinding elements, about to be described, and by removing the motor 11 and the cover-plate 9, access may be had to the various elements of the speed reduction and driving mechanism.

20 The lower end of the main shaft 22 is of square or other angular section and extends through central openings in the movable grinding rings or discs 26 and 27, the openings being slightly larger than the shaft, whereby the 25 rings are permitted a limited vertical as well as horizontal movement to maintain alignment regardless of any inaccuracies in manufacture or normal wear of the grinding elements. The under surface of the grinding ring 26 is provided 30 with a circumferential channel 28, having a curvature corresponding to the annular series of grinding balls 29, which travel in a channel formed in the upper surface of the fixed ring 6. The under surface of the fixed ring 6 is likewise 35 provided with a circumferential groove or channel corresponding to the surface 28 of the movable ring 26, to form the upper race-way for a second series of balls 30, which are carried in a similar race-way or grinding surface on the upper 40 surface of the ring 27. Each of the said grinding surfaces or race-ways is preferably chilled, and it is to be noted that the design is such that the castings can be made without employing angular chills.

45 The rotating rings 26 and 27 are apertured to receive a plurality of spring rods 31, carrying compression springs 32, the compression of which may be adjusted by suitable collars and nuts indicated generally at 33.

50 It will be seen that the fixed grinding ring 6 carries the weight of the rotating grinding rings 26 and 27, together with the grinding balls 29 and 30 of the first and second grinding stages, whereby the crushing effect is vastly greater than in older types of mills. The weight of these parts 55 is preferably less than that necessary to effect the initial stage of reduction and the additional pressure is transmitted to the balls 29 of the first stage by the effect of the springs 32, carried by the spring rods 31. Accordingly, the pressure on 60 the balls 30 of the second stage can be held at the minimum necessary to complete the reduction, and without carrying an excessive load, which would have no substantial effect in grinding, but would merely add to the power requirement and the rate of wear. It will be understood 65 that with many materials, a second stage of grinding can be carried out more economically by a higher degree of attrition relatively to the crushing effect, and accordingly although the balls 30 are shown as of the same size as the balls 29, the second stage may comprise a greater number of smaller balls to increase the number of lines of contact.

70 75 In order to control the degree of fineness, a

circular dam 34 is secured to the outer edge of the grinding ring 27, the dam being adjustably secured as to height by means of the set screws 35. By increasing the height of the dam relatively to the fixed ring, the material discharging over the 5 dam will be of greater fineness, and it will be realized that inasmuch as the grinding elements are not air-swept, the product will be of unusual uniformity.

Below the rotating ring 27, the lower section 2 10 of the mill casing is provided with a circular series of air ports 36, through which air for sweeping and forwarding the material is induced by means of the fan 37. The casing of this fan has an upper conical section 38, which closes the 15 under side of the mill. Interposed between the base of the mill and the conical section 38 is a grating 39, which may be a perforated plate, the total area of the openings of which is preferably at least equal to the area of the ports 36, to 20 decrease the resistance to air flow, the openings being small enough to trap tramp material of sizes liable to damage the fan, such material being removable through the ports 36. The fan is driven by a shaft 40, which passes upwardly 25 through a bore 41 in the main driving shaft 22 and is secured to the hub of the pinion 16. The lower end of the shaft is supported for rotation in a ball bearing 42, carried in the lower section 43 of the fan casing. It will thus be seen that 30 the motor 11 drives the fan 37 at full load speed, whereas the grinding balls are driven circumferentially of the mill at a speed which preferably corresponds to the gravity fall of material 35 by the effect of the speed reduction gearing above described.

The operation of the apparatus will be evident from the above description, but it is to be realized that the material discharged from the feeder 14 into the central section 3 falls upon the upper 40 surface of the rotating ring 26, which distributes the material around the grinding elements of the first stage. The falling material passes inwardly 45 through the balls 29, and falls through the space between the inner edge of the fixed ring 6 and the outer surface of the movable ring 27, the lower part of which slopes outwardly to guide the material to the raceway of the balls 30. To vary the pressure of the grinding elements, the compression of the springs 32 is changed by means of 50 the nuts 33, access to which may be through the air inlet ports 36, and the degree of fineness 55 finally established by the elevation of the dam 34.

As will appear more clearly from Fig. 2, little change is required in the parts or their arrangement to adapt the mill for wet grinding. For this use, water may be added to the materials entering the mill, or through a nozzle indicated generally at 44. An additional circular dam 45 is provided and secured adjustably to the inner 60 edge of the fixed grinding ring 6 to control the fineness of the product discharged from the first stage. As compared with the arrangement shown in Fig. 1, the lower section 2 is solid, and a slurry pump 46 is substituted for the fan 37. 65 This pump may likewise be driven in the same manner, and the shaft 40 being similarly carried in a bearing 47 in the bottom of the pump casing.

It will be understood that although I have 70 shown and described the preferred form of the invention as comprising two grinding stages, that one or more additional stages can be applied, where the characteristics of the material to be ground, and the fineness of the product de- 75

sired, makes two or more secondary stages desirable. Such an arrangement is shown in Fig. 3, wherein I have also shown the necessary changes and additions required to adapt the mill for reducing damp materials, such as raw coal. It is to be understood that these changes and additions are likewise adaptable to a two-stage mill of the type shown in Fig. 1.

In this arrangement an additional or intermediate section of the casing is provided at 48 to provide space for the third stage, which comprises an additional fixed grinding ring 49, having a sloping upper surface 50 to divert the descending material to the outer surface of a third movable grinding ring 51. The under surface of the fixed ring is provided with a circumferential channel, similar to those above described, and the upper surface of the ring 51 with a similar channel to form a race-way for the balls 52. The spring rods 31 are preferably inverted, with the springs 33 arranged at the top to avoid interference with the rotating ring 51, and additional spring rods 53, arranged alternately on the same circle, but of greater length than the rods 31, are provided to support the rotating ring 51 and provide the desired pressure on the balls 52.

In view of the increased length of the fan shaft 40, and of the main driving shaft 22, which has been extended in order to drive the ring 51, a guide-bearing 54 surrounds the shaft 40 and is retained in a bore formed at the bottom of the shaft 22.

To dry the damp material, preheated air from any suitable source is forced or drawn into a volute casing or wind box 55 and enters the ports 36. The lower grinding ring 51 is provided with a circular series of apertures, 56, and the ring 27 with apertures 57. The area of said apertures is less than that of the apertures 58, provided in the upper grinding ring 26, whereby air drawn upwardly through the mill and ultimately discharging through the opening 59, due to the action of the usual exhaust fan (not shown), will be divided in its passage through the second and third stages, and a portion will pass between the balls of the said stages. The greater area of the openings 58 causes substantially all of the air to pass over the baffle 60, formed on the upper surface of the ring 26, the baffle serving both to limit the quantity of fines passing out of the opening 59, and also to prevent material entering through the feeder from short-circuiting the first stage through the openings 58. The moisture-laden air passing out of the mill may be conducted from the opening 59 to any suitable type of air separator (not shown) for recovering any fine particles that may be carried in suspension.

It is to be understood that the actual removal of material from the mill, or classification of the final product, is substantially the same as that described with reference to Fig. 1 and that the quantity of drying air is preferably limited to the minimum quantity as influenced by the material moisture content, temperature and humidity of the gas, as will permit efficient grinding, in order to prevent actual air-sweeping of the mill.

I claim:

1. A pulverizing mill comprising the combination of a cylindrical casing including a lower, fixed casing section and an upper removable casing section, a grinding assembly arranged in the casing and including a non-rotary grinding ring, a rotating grinding ring operatively related thereto, an annular series of grinding elements operative between said rings, and means for exerting

yielding grinding pressure on the grinding elements, the lower casing section being provided with means forming a support for the non-rotary grinding ring and hence for the grinding assembly, the rotating ring having a central opening, a horizontally extending supporting element disposed above the grinding assembly and arranged intermediate said casing sections and removably supported from the lower casing section, the supporting element having a central opening and forming with the upper casing section a compartment, a driving mechanism disposed in said compartment and including coaxially arranged driving means, driven means supported for rotation on said element, and a main drive shaft secured to said driven means, said drive shaft extending through the openings of said supporting element and the rotating grinding ring, and being supported for rotation by said element and having a driving connection with said rotating grinding ring, the arrangement being such that the driving mechanism including the main driving shaft and the supporting element may be raised bodily from the grinding assembly and the lower casing section, and that the grinding assembly may thereupon be raised bodily from the lower casing section.

2. A pulverizing mill comprising the combination of a cylindrical casing including a lower, fixed casing section and an upper removable casing section, a grinding assembly arranged in the casing and including a non-rotary grinding ring, a rotating grinding ring operatively related thereto, an annular series of grinding elements operative between said rings, and means for exerting yielding grinding pressure on said elements, the lower casing section being provided with means forming a support for the non-rotary grinding ring and hence for the grinding assembly, the rotating ring having a central opening, a driving assembly for the rotating ring, means for supporting the driving assembly above the grinding assembly including a supporting element arranged intermediate said casing sections and removable with respect to the lower casing section, the supporting element having a central opening, the driving assembly including a main driving shaft extending through the openings of the element and the rotating ring and having a driving connection with the latter, a ring gear having a driving connection with the shaft and supported for rotation on the supporting element, a source of power, and gearing between the power source and the ring gear, the arrangement being such that the driving assembly including the main driving shaft and the supporting element may be raised bodily from the grinding assembly and the lower casing section, and that the grinding assembly may thereupon be raised bodily from the lower casing section.

3. A pulverizer mill comprising the combination of a cylindrical casing comprising a plurality of vertically arranged removable sections, a fixed grinding ring carried by a lower section, a rotating grinding ring operatively related thereto, an annular series of grinding elements operative between the rings, means rotating with the rotating grinding ring for exerting yielding grinding pressure on the grinding elements and for securing the rings and elements together as an assembly-unit, the rotating ring having a central opening, a driving assembly for the ring supported independently thereof, comprising a support carried by a section above the fixed ring, the vertical section above the fixed ring, the support, and the

drive means being removably supported by said fixed ring, a main drive shaft carried by and extending through the support and into the opening to engage the walls thereof, and speed reduction means arranged symmetrically about the axis of the mill, including a ring gear concentric to the shaft and secured thereto, at least two oppositely arranged idler gears within and meshing with the ring gear and a central pinion for driving the idler gears.

4. A pulverizer mill comprising the combination of a cylindrical casing comprising a plurality of vertically arranged sections, a fixed grinding ring carried by a lower section, a rotating grinding ring operatively related thereto, an annular series of grinding elements operative between the rings, means rotating with the rotating grinding ring for exerting yielding grinding pressure on the grinding elements and for securing the rings and elements together as an assembly-unit, the rotating ring having a central opening, a driving assembly for the ring supported independently thereof, comprising a support carried by a section above the fixed ring, a main drive shaft extending through the support and into the opening to engage the walls thereof, and speed reduction means arranged symmetrically about the axis of the mill, including a spider connected to the shaft and carrying a ring gear, at least two oppositely arranged idler gears meshing with the ring gear, each of said gears being enclosed within another section of the casing above the support, the section having a cover-plate enclosing the mill, a vertical motor carried by said cover-plate and secured centrally thereof, the motor having a shaft extending through the cover-plate and carrying a pinion meshing with the idler gears for driving the latter.

5. A pulverizer mill comprising the combination of a casing, a fixed grinding ring carried by the casing, a rotating grinding ring operatively related thereto, an annular series of grinding elements operative between the rings, the rotating grinding ring having a central opening, a fan for forwarding pulverized material and means for driving the rotating grinding ring at relatively slow speed and the fan at relatively high speed from the same source of power comprising a main driving shaft extending into the opening in the rotating grinding ring and engaging the walls thereof, speed reduction means for driving the shaft, the shaft having a central bore, a fan shaft extending through the bore and connected to the fan, and common means for driving the fan shaft and the speed reduction means.

6. A pulverizer mill comprising the combination of a casing, a fixed grinding ring carried by the casing a rotating grinding ring operatively related thereto, an annular series of grinding elements operative between the rings, the rotating grinding ring having a central opening, a fan below the grinding rings for forwarding pulverized material, and means above the rings for driving the rotating ring at relatively slow speed and the fan at relatively high speed from the same source of power, comprising a main driving shaft extending downwardly into the opening in the rotating grinding ring and engaging the walls thereof, speed reduction means for driving the shaft, the shaft having a central bore, a fan shaft extending through the bore and connected to the fan, and common means for driving the fan shaft and the speed reduction means.

7. A pulverizer mill comprising the combina-

tion of a casing, a fixed grinding ring carried by the casing a rotating grinding ring operatively related thereto, an annular series of grinding elements operative between the rings, the rotating grinding ring having a central opening, discharge means, for pulverized material, below the fixed ring, and means above the rotating ring for driving the rotating grinding ring at relatively slow speed and the discharge means at relatively high speed from the same source of power, comprising a main driving shaft, extending downwardly into the opening in the rotating grinding ring and engaging the walls thereof, speed reduction means for driving the shaft, the shaft having a central bore, a second shaft extending through the bore and connected to the discharge means, and common means for driving said second shaft and the speed reduction means.

8. A pulverizer mill comprising the combination of a casing, a fixed grinding ring carried by the casing and having a grinding surface on its lower side, an annular series of grinding elements engaging said surface, a rotating grinding ring supporting said grinding elements, means for delivering material thereto, means to drive the rotating grinding ring, a cylindrical classifying dam secured to the peripheral portion of the rotating grinding ring and on the discharge side thereof, the dam being vertically adjustable to control the degree of fineness of the ground material discharging thereover, the casing being provided with air inlets located immediately below the rotating grinding ring, a fan located below said inlets and having its suction side opening into the lower portion of the casing whereby to induce an air stream through said inlets and into which the ground material discharging over said dam falls, said fan being concentric with said rotating ring driving means and being driven thereby.

9. A gravity-discharge pulverizer mill for reducing damp materials, having at least two grinding stages comprising the combination of a casing, a fixed grinding ring carried by the casing and having a central passage for air and material and a grinding surface on its upper side, an annular series of grinding elements on said surface, a rotating grinding ring resting upon and carried by said elements, a second rotating grinding ring below and yieldingly supported by the first and having a grinding surface on its upper side, a second series of grinding elements on said surface in engagement with an under surface of the fixed ring, each of said rotating rings being provided with openings within said central passage for the flow of air, the casing being provided with an air inlet below the second grinding ring adapted to admit drying air, the casing being also provided with an outlet above the rotating rings through which at least a part of the air entering the inlet may be drawn to provide a counter-current of air for driving the material, the material passing downwardly through said grinding stages in opposition to the countercurrent.

10. A pulverizer mill comprising the combination of a casing, a fixed grinding ring carried by the casing and having a grinding surface on its lower side, an annular series of grinding elements engaging said surface, a rotating grinding ring having a rim portion provided with a substantially horizontal upper face, a grinding surface on said upper face disposed adjacent the peripheral edge of the ring, the rotating ring being arranged below the fixed ring and supporting the

- grinding elements, means rotating with the rotating ring for exerting a yielding upward pressure on the rotating grinding ring and grinding elements supported thereby, means for feeding material to be pulverized to the inner side of the grinding elements for movement outwardly across the grinding surfaces, a cylindrical element removably mounted on the outer peripheral face of the rotating grinding ring and extending above the level of said peripheral edge, said element functioning as a dam for retarding discharge of the pulverized material and being vertically adjustable with reference to the rotating grinding ring.
15. 11. A pulverizer mill comprising the combination of a cylindrical casing including a lower fixed casing section, an upper removable casing section, and a member arranged intermediate said sections and removably supported from the lower section, the intermediate member dividing the casing into upper and lower compartments and having a drive shaft opening, a grinding assembly including a non-rotary grinding ring, a rotating grinding ring having a drive shaft opening therethrough, said rings each having a circumferential ball channel and said channels being vertically aligned, an annular series of grinding balls disposed in said channels, and means

rotating with the rotating grinding ring for exerting yielding grinding pressure on the grinding balls and for securing the rings and balls together as an assembly-unit, means including the lower casing section providing a support for the non-rotary ring and hence for the grinding assembly-unit, from which support the grinding assembly-unit is readily removable, a driving assembly contained in the upper compartment and supported by the intermediate member, the driving assembly including a drive shaft which extends downwardly through the aforesaid shaft openings and has a driving connection with the rotating grinding ring, means for directing material to be pulverized to the grinding assembly including a casing inlet disposed below the intermediate member, the lower casing section having an opening for the discharge of pulverized material from the casing, and the arrangement being such that the upper casing section may be removed to provide access to the driving assembly and that the upper section, the driving assembly, and the intermediate member may be raised bodily from the casing, and the grinding assembly-unit thereupon raised from the lower casing section.

HARRY R. COLLINS.
